BEAM WRAPPING

Calvin A. Kemper, Chicago, Ill.

Application November 19, 1932, Serial No. 643,465

2 Claims. (Cl. 72—109)

This invention relates to improvements in beam wrapping which is used to reinforce concrete placed around steel beams for fireproofing the same, or for other purposes.

5 There are various forms of beam wrapping on the market at the present time, which have certain disadvantageous features which the present improvements are designed to remedy.

For example, one widely used wrapping, while 10 it is expandable to enable the same to be used on beams of different widths, is so constructed that upon lateral expansion it is longitudinally shortened, and while wrapping of this character is frequently sold in standard lengths, this fore- 15 shortening due to lateral expansion, renders difficult the accurate calculation of the lineal feet of wrapping required for any particular job.

Another disadvantage of the type mentioned 20 and other types on the market is that the longitudinal reinforcing rods or wires are not arranged so as to provide adequate reinforcement for the concrete at the corners of a beam, which frequently necessitates that workmen wire or otherwise attach reinforcing rods to the wrapping in order that the construction specifications 25 be complied with.

An object of the present invention is to provide a wrapping structure which remedies the 30 above mentioned disadvantages and others by the provision of a wrapping comprising trans- 35 verse clips which are expandable to enable their use on beams of varying sizes, and having longitudinal reinforcing wires which are not shortened by the expansion of the clips, the arrangement of the longitudinal reinforcing being such that the corners of the concrete enclosing a beam will be adequately reinforced and also spaced suitably from the face of the beam.

Other objects relate to various features of construction which will be apparent from a consideration of the following specification and accom- 40 panying drawing, wherein

Figure 1 is a transverse section through an I-beam showing the improved beam wrapping 45 attached thereto,

Figure 2 is a similar view showing the beam wrapping in expanded position and attached to a wider beam in a slightly different manner.

Figure 3 is a side elevation of a section of 50 wrapping, and

Figure 4 is a broken transverse section of a beam showing the improved wrapping thereon, but having a different number of longitudinal reinforcing wires or bars.

55 In the drawing, 10 indicates a conventional

steel beam such as may be used in the erection of buildings for example, and which generally are enclosed in concrete for fire proofing purposes. As is known, forms are secured around the beams into which the concrete is placed. 5 However, it is frequently necessary that this concrete be suitably reinforced and in the drawing a beam wrapping embodying the present improvements is shown attached to one flange only of the beam.

The beam wrapping preferably comprises a plurality of longitudinally extending reinforcing wires or rods 11 which may be welded to the transverse clips which are indicated generally by the numeral 12.

In the form of the invention shown, each clip is provided with a central portion which is re- 10 versely bent to form folds or convolutions 13 which permit of the expansion of the clips to enable the same to be attached to beams of vari- 15 ous widths. Thus in Figure 2 the transverse member 12 is shown expanded to accommodate the beam 14 having flanges wider than the flanges of beam 10. The lateral or end folds or convolutions of the member 12 as shown in Figure 1, 3 and 4, terminate in arms 15 which may be bent over the rear of the adjacent flanges of the beam to hold the wrapping in position. The arms may be sufficiently long, however, to ex- 20 tend over the opposite flange and be bent over the diagonal corner of the beam as shown at 15a in Figure 2, where the building specification renders this mode of attachment desirable. The reinforcing rods 11 preferably are secured to these lateral folds as shown in the drawing. It 25 is preferred to weld the rods in position.

It will be seen from an examination of Figures 1 and 2 that this construction of the wrapping is such that reinforcing rods 11 will always be positioned adjacent the corners of the beam to provide adequate reinforcement at these places. If desired additional reinforcing rods such as rod 17 may be secured to the intermediate folds. By 30 this construction the improved wrapping can be attached readily to beams or other structures by 35 means of the arms 15 or 15a. The folds 13 of each transverse member 12 are disposed sub- 40 stantially at right angles to the face of the beam and serve as spacing members to space the intermediate rods a suitable distance from the face 45 of the beam. As many members 12 per section of wrapping may be used as may be desired either to support the longitudinal rods or to provide 50 reinforcement supplemental to that provided by the rods.

It will also be apparent that the expansion of the transverse member does not effect a fore-shortening of the reinforcing rods 11 as in certain types of present day wrapping.

5 Other shapes of folds may, of course, be used but the plait-like folds of the transverse members or clips is preferred.

Another advantageous feature of the present invention resides in the fact that as the clips are 10 extended, the portions 18 maintain their angular relation with respect to the arms 15 and thus serve to space the rods 11 a uniform distance from the face of the beam. This result accrues not only because of the angular disposition of the 15 portions 18 which is shown as being approximately forty-five degrees with respect to arms 15, but because the reinforcing rods 11 are seated in the acute angles formed by arms 15 and portions 18 and are welded to the same. The intermediate rods 17 are also preferably welded in 20 position but due to the curvature of the ends of the folds to which the rods are attached, the welded connection does not limit the flexing of the intermediate portion of the clips. A further 25 advantage of the present construction resides in the fact that additional longitudinal supporting rods may be positioned in folds of the clips by workmen after a section of wrapping has been secured to a beam where such additional reinforcing is considered advisable. In such instances the rods may be wired in place, if desired, or may be loosely positioned in the folds of the clips which will support the additional rods in horizontal alignment and in spaced relation 30 with respect to the other intermediate rods which may have been welded in place at the factory. Thus in Figure 4 a wrapping is shown, the 35 clips of which are provided with additional folds for accommodating a greater number of intermediate rods 17, all of which may be welded in 40

place or some of which may be positioned by workmen after the wrapping has been attached to a beam.

While I have shown and described an embodiment of my present improvements for the purpose of illustration, I do not wish to be restricted specifically thereto except as so limited by the appended claims.

I claim:

1. A concrete reinforcing device fabricated in 10 a predetermined length comprising a plurality of transverse members each having an intermediate portion and supporting arms at each end thereof arranged substantially at right angles to the face of a supporting structure, said intermediate portions being provided with one or more extensible plait-like folds to enable the members to be extended transversely of said structure, and longitudinal reinforcing members secured to said transverse members adjacent the juncture of 15 said intermediate portions and said arms whereby by said reinforcing members will always be located adjacent a corner of the concrete enclosing said structure regardless of the degree of extension of said transverse members.

2. A reinforcing structure fabricated in predetermined lengths comprising a plurality of transverse members having supporting arms at the ends thereof and one or more extensible intermediate folds integrally united to said arms by 30 portions forming acute angles therewith, and longitudinal reinforcing members positioned within the angle at the juncture of said portions and arms and being welded to the same to thereby resist change in the angular relation of said 35 portions with said arms when said transverse members are extended whereby said portions will space said reinforcing members uniformly from a supporting structure.
